United States Patent Office.

DAVID R. QUICK, OF NEW YORK, N. Y.

Letters Patent No. 94,439, dated August 31, 1869.

IMPROVEMENT IN JOURNALS.

The Schedule referred to in these Letters Patent and making part of the same.

To all whom it may concern:

Be it known that I, DAVID R. QUICK, of New York city, in the county of New York, and State of New York, have invented a new and valuable Improvement in Journal-Boxes; and I do hereby declare that the following is a full, clear, and exact description of the construction and operation of the same, reference being had to the annexed drawings, making a part of this specification, and to the letters and figures of reference marked thereon.

Figure 1, of the drawings, is a plan view of my invention.

Figure 2 is a sectional view of the same.

Figures 3, 4, and 5, are details.

My invention relates to journal-boxes; and

It consists, mainly, in a novel arrangement of devices intended to serve as efficient means for the purpose named.

The letter A, of the drawings, represents a shaft, arranged in my journal-box;

Letter B, the hanger; and

Letter C, the box.

My journal-box is constructed in two sections, marked respectively a and c upon the drawings, each of which has an opening, s, through which the hanger is passed, and a semicircular opening, v, through which the shaft passes. These two semicircular openings v, when united, serve to clasp the shaft, and hold it firmly in place.

It will be observed that the openings s are made at right angles with the openings v.

The letters y represent India-rubber rings, arranged upon the hanger, at each end of the openings s, and

The letter n, a nut, working on a thread on the end of the hanger, as shown.

I usually place a thin metallic washer between the nut n and a ring, y. Such a washer is shown on the drawings, at the point h.

In the manufacture of these boxes, care must be taken to place suitable boxings at each end of the openings v, in order to prevent unnecessary wear thereon.

Washers of wood will serve a valuable purpose, if properly arranged, at the point h.

What I claim as my invention, and desire to secure by Letters Patent, is—

The arrangement of the journal-box and shaft herein described, consisting of the sections a and c, openings s and v, rings y, washer h, and nut n, with reference to the shaft, substantially as specified.

In testimony that I claim the above, I have hereunto subscribed my name, in the presence of two witnesses.

DAVID R. QUICK.
